UNITED STATES PATENT OFFICE.

CHARLES G. SHEPARD AND PETER ADAMS, OF BUFFALO, NEW YORK; SAID
ADAMS ASSIGNOR TO WALTER J. SHEPARD, OF SAME PLACE.

TOY PISTOL.

SPECIFICATION forming part of Letters Patent No. 372,990, dated November 8, 1887.

Application filed February 28, 1887. Serial No. 229,144. (No model.)

To all whom it may concern:

Be it known that we, CHARLES G. SHEPARD and PETER ADAMS, both of the city of Buffalo, in the county of Erie and State of New York, have invented a new and useful Improvement in Toy Pistols, of which the following is a specification.

This invention relates to that class of toy pistols which are designed for exploding caps. 10 The object of our invention is to produce an attractive and durable toy of this kind which is simple and inexpensive in construction; and the invention consists of the improvements which will be hereinafter described, and pointed out in the claims.

In the accompanying drawings, Figure 1 represents a perspective view of our improved toy pistol. Fig. 2 is a sectional side elevation of a portion or side of the frame of the pistol, 20 showing the interior mechanism. Fig. 3 is a side elevation of the other portion or side of the frame of the pistol. Figs. 4 and 5 are cross-sections in lines *x x* and *y y* of Fig. 2, respectively.

Like letters of reference refer to like parts in the several figures.

The frame or body A of the toy is constructed to represent the figure of a monkey perched upon a base or support, A', which latter forms 30 a handle for the pistol. For convenience of manufacture the frame A is composed of two similar portions, B B', which are secured together by transverse bolts or rivets *b*, the portion B of the frame being formed with the base A'.

C represents a sliding bolt or rod arranged in the frame A and seated in semicircular bearings *c e*, formed in the inner adjacent sides of the two halves or portions B B' of the frame. 40 The head *c'* of the bolt projects through an opening, *d*, formed in the front side or neck of the portions B B' of the frame and forms the lower jaw of the monkey. The bolt C is provided at its inner end with an arm or finger-piece, *e*, which projects outwardly through a slot, *f*, formed in the portion B'. The bolt C forms the hammer for the pistol, and its head *c'* bears against a flat face or shoulder, *g*, formed on the adjacent front sides of the portions B

B' above the opening *d*. The shoulder *g* forms 50 the upper jaw of the monkey.

g' is the recess formed in the frame A below the fixed jaw *g* for the reception of the caps.

h represents a spiral spring which surrounds the bolt C, whereby the head of the bolt or 55 the lower jaw, *c'*, is held against the shoulder or upper jaw, *g*. The spring *h* is arranged on the bolt C between one of the bearings *c* and a flange or collar, *h'*, formed on the bolt, so that the spring *h* is compressed upon moving the 60 head of the bolt away from the shoulder or jaw *g*.

I represents the trigger, pivoted between the two portions B B' of the frame by a pivot or pin, *i*, cast on the inner side of the portion B, and engaging in an opening, *i'*, formed in the 65 trigger. The trigger *I* is provided with a tail-piece, *j*, whereby the trigger is operated. The tail-piece *j* forms the tail of the monkey and projects outwardly through a slot, *k*, formed in the adjacent rear edges of the portions B B'. 70

l represents a nose or projection formed on the trigger *I* and adapted to engage over a lug or shoulder, *m*, formed on the inner end of the hammer C, when the latter is moved inwardly with its head away from the jaw *g*; by 75 pressing on the finger-piece *e*. The nose *l* of the trigger is held in engagement with the lug *m* by a spring, *n*, which bears against the under side of the trigger. The inner end of the hammer C below the lug *m* is beveled or inclined, as shown at *o*, so that upon drawing the hammer C inwardly by the finger-piece *e* the inclined face *o* will force the trigger backward until its nose *l* has engaged itself over the lug *m*. The spring *n* rests upon the edge of 80 the slot *k* and fits over a pin, *q*, formed on the under side of the trigger, so as to force the nose *l* of the trigger forward against the inclined edge *o*. When the head of the hammer C is drawn away from the jaw *g*, and is locked 85 in this position by the trigger, as shown in Fig. 2, the cap to be exploded is inserted between the two jaws of the figure, and upon pressing down upon the tail-piece *j* the bolt is released and is forced outward by the spring 90 *h*, causing the hammer to strike against the jaw *g* with sufficient force to explode the cap. 95

The outer edge of the head *c'* of the hammer

is provided with an upwardly-projecting rim, *r*, which fits in a notch, *s*, formed in the jaw *g*, when the head *c'* is closed against the jaw *g*.

The rim *r* forms a guard for the cap and retains the latter in place upon the head of the hammer.

We claim as our invention—

1. In a toy pistol, the combination, with the frame *A*, having a fixed jaw, *g*, and a recess, *g'*, adjacent to said jaw, of a sliding bolt, *C*, provided with a jaw, *c'*, moving in the recess *g'*, a spring, *h*, whereby the bolt *C* is projected, with the jaw *c'*, against the fixed jaw *g*, and a trigger engaging with the bolt *C*, substantially as set forth.

2. In a toy pistol, the combination, with the frame *A*, having a fixed jaw, *g*, and a recess, *g'*, adjacent to said jaw, of a sliding bolt, *C*, provided with a jaw, *c'*, moving in the recess *g'*, and a thumb-piece, *e*, a spring, *h*, applied to the bolt *C*, a trigger, *I*, pivoted in the frame *A* and provided with a projecting tail-piece, *j*, and a spring, *n*, whereby the trigger is held

in engagement with the sliding bolt, substantially as set forth.

3. In a toy pistol, the combination, with the figure *A*, composed of two similar parts, *B* *B*, and provided with a jaw, *g*, of a sliding bolt, *C*, arranged in the figure and provided with a spring, *h*, whereby the head of the bolt is held against the jaw *g*, a finger-piece, *e*, formed on the inner end of the bolt and extending through an opening in the figure, a trigger, *I*, provided with a nose, *l*, adapted to engage over a lug, *m*, on the inner end of the bolt, and a spring, *n*, bearing against the under side of the trigger, substantially as set forth.

Witnesses our hands this 18th day of February, 1887.

CHARLES G. SHEPARD.
PETER ADAMS.
